UNITED STATES PATENT OFFICE.

GEORGE HILGER, OF CHICAGO, ILLINOIS.

VENTILATING SYSTEM.

Application filed March 4, 1927. Serial No. 172,850.

This invention pertains to improvements in ventilating systems and has more particular reference to the ventilation of coolers, refrigerators and other closed compartments by the natural circulation of air therethrough.

Many food products when stored in a closed refrigerator compartment give off foul and ill-smelling gases comprising various organic derivatives which, being lighter than air, tend to collect in the upper portion of the compartment. This is especially true in the case of meat and butter which have started to deteriorate before being placed in storage. Oftentimes these gases accumulate in such quantities that they may condense and fall upon the products in storage. Such conditions are objectionable not only because of the offensive odors about the storage chamber but also because the presence of these gases and the condensate thereof tend to start or accelerate decomposition of the products in storage.

The primary object of the present invention is to overcome these difficulties by providing a new and improved means for ventilating refrigerators and other cold-storage compartments, which does not reduce materially the efficiency of the cooling system employed and which operates at all times to keep the compartment and the adjacent rooms sweet and clean.

More specifically stated, the invention aims to provide a novel circulatory system for the natural ventilation of coolers, refrigerators and the like by which foul gases accumulating therein are removed slowly and continuously from the building where the compartment is located and replaced by fresh air.

Another object is to provide an automatic control for a circulatory system of ventilation so that the system will operate efficiently regardless of changes in temperature conditions outside of the system.

Still a further object is to adapt the present system of circulation control to a plurality of compartments to be ventilated.

Other objects and advantages will become apparent from the following detailed description taken in connection with the accompanying drawings, in which

Figure 1 is a vertical sectional view of a refrigerator compartment equipped with my improved ventilating system, the latter being shown somewhat diagrammatically.

Fig. 2 is a plan section of the refrigerator room with the top wall thereof removed.

Fig. 3 is a detailed view showing a portion of the control means for the ventilating system.

Fig. 4 is a vertical sectional view of three refrigeration compartments arranged to be ventilated by the present system.

Fig. 5 is a side elevational view of the compartments shown in Fig. 4.

While I have shown in the drawings and will herein describe the preferred embodiment of the invention, it is to be understood that I do not intend to be limited thereby to the particular form disclosed but aim to cover all modifications and alternative constructions falling within the spirit and scope of the appended claims.

The invention is illustrated in Figs. 1 and 2 of the drawings as applied to a refrigerator compartment 10 having a top wall 11, a bottom wall 12, end walls 13 and 14, and side walls 15 and 16. The end wall 14 is spaced a short distance from the wall 16 of the building in which the compartment is located.

As is common practice in the art, the compartment is arranged to be refrigerated artificially by a coil 17 supported along the side wall 16 and by end coils 18. These coils may be connected in series and adapted to be supplied with a refrigerant by any preferred form of refrigeration unit.

In the present instance, the air from the upper portion of the cooling compartment where the foul gases usually collect, is intended to be removed and delivered to the atmosphere outside of the building and fresh air from the outside is admitted into the compartment to replace the gases thus removed. To this end, an exhaust header 19 is located in the upper portion of the compartment near the side wall 16 in communication with three pipes 20 preferably located at opposite ends and in the center of the compartment just below the top wall 11. Each pipe has a series of perforations through which air from the upper part of the compartment may pass into the header. Two outlet ducts are provided for the header 19 one comprising a pipe 21 communicating with one end of the header and extending through the end wall 14 of the compartment near the upper portion thereof and terminating outside of the wall 16 of the building. The other outlet duct comprises a pipe

22 connecting the medial portion of the header 19 with one end of a jacket 23, the other end of which leads outside of the building through a pipe 24 extending 5 through the walls 14 and 16 near the lower portion of the cooling compartment. Preferably the jacket 23 is mounted on and encircles one pipe of the refrigeration coil 17, the air within the jacket being thereby directly cooled by the refrigeration pipe. The outlet ducts may be controlled by ordinary gate valves 26 and 27 located within the building and outside of the cooling compartment. In the preferred embodiment, the movable members of these valves are connected by a rigid rod 28, the arrangement being such that one valve will be open while the other is closed. The air removed from the compartment through the exhaust 20 header and the outlet ducts is intended to be replaced by fresh air admitted to the compartment through either of two inlet ducts located respectively near the upper and lower portion of the end wall 14. These 25 ducts comprise pipes 29 and 30 and are arranged to be opened and closed respectively by gate valves 31 and 32 having their movable valve members connected to the rod 28 in such a way that the upper valve 31 will 30 be open only when the lower gate valve 27 is open and will be closed when the upper gate valve 26 and the lower valve 32 are open.

Means is provided for controlling the setting of the valves 26, 27, 31 and 32 in accordance with the temperature difference between the cooling compartment 10 and the air outside of the building. Preferably this means comprises a lever 33 arranged to be moved to one position or the other by a double diaphragm actuator unit 34. This unit (see Fig. 3) comprises a casting 35 having heads 36 secured to its opposite ends. Flexible diaphragms 37 are clamped between 40 the casting and the heads and define chambers 38 which communicate through ducts 39 and 40 with thermal responsive elements 41 and 42. Each element together with the corresponding chamber 38 is filled with a 45 thermal responsive gas such as ammonia from the refrigeration system. The two diaphragms are connected by a rigid rod 43 which is arranged to operate the lever 33. The latter is pivoted intermediate its ends on 50 the casting 35 and one end carries an adjusting weight 44 while the other is pivotally connected with the rod 28.

The pressure element 42 is placed within the cooling compartment while the element 60 41 is placed in the open air outside of the building. It will be apparent that the diaphragm unit may be adjusted by means of the weight 44 to respond to a predetermined variation between the temperatures of the 65 compartment 10 and the outside air. Pref-

erably the unit 34 is set so that when the outside temperature becomes greater than the temperature inside of the compartment, the rod 28 will be raised into the position shown in Fig. 1 thereby opening valves 27 70 and 31 and closing valves 26 and 32, and when the temperature outside becomes lower than that of the compartment, the diaphragms will be flexed upwardly and the rod 28 will be moved downwardly opening 75 valves 26 and 32 and closing valves 27 and 31.

It will be seen that with the above arrangement of inlet and outlet valves, two paths for circulation of air through the 80 cooling compartment 10 are provided, each corresponding to one position of the actuator rod 28. When the rod is in raised position, as shown in Fig. 1, air may enter the compartment 10 through the inlet duct 31 and 85 may leave through the exhaust header 19 and the outlet pipe 24. When the rod is lowered, the air may enter through the inlet duct 30 and leave through the exhaust header and the outlet pipe 21. In each instance, the air is removed from the upper portion of the cooling compartment.

The operation of the present system may be considered as being based on the tendency of a gas of a given density to circulate 95 downwardly or upwardly relative to a gas of different density. In the present instance, the difference in densities is caused by the difference in temperature between the outside air and that within the cooling compartment. 100

The operation will first be considered under conditions where the compartment 10 is cooler than the outside air as would be the case during most of the months of the year. 105 Under these conditions (Fig. 1) valves 27 and 31 would be open and valves 26 and 32 would be closed, and circulation would take place as follows: The air in the pipe 22 and within the jacket 23 being in close proximity to the cooling coil 17 would be cooled below the average temperature of the air within the compartment 10. The density of the air would thus be increased with the result that the air would pass out through the 115 valve 27 and pipe 24 into the lighter air outside of the building. This would induce circulation of the foul gases from the upper portion of the compartment into the exhaust header through the perforations in the pipes 20. Such removal of air creates a slight 120 vacuum within the compartment with the result that fresh air would be drawn in through the duct 29 which is then opened. In this way a slow and uniform circulation of air through the compartment is effected, the foul air accumulating in the upper portion of the compartment being thereby removed.

When the temperature conditions are 130

reversed, that is, when the outside air becomes cooler than the compartment as would frequently be the case during winter months, the diaphragm unit would respond 5 automatically to shift the rod 28 downwardly, thereby closing the valves 27 and 31 and opening the valves 26 and 32. Under these conditions, the air within the compartment, being warmer and therefore lighter 10 than the outside air, would tend to flow out of the compartment through the upper pipe 21. Also the colder and heavier outside air would tend to circulate into the compartment through the lower pipe 30. This combined inflow and outflow provides for removal of the foul gases from the upper portion of the storage compartment.

In Figs. 4 and 5, the invention is illustrated as applied to a series of three vertically disposed refrigeration compartments 46, 47 and 48, the arrangement being such that only one diaphragm control unit is required and such that any one of the compartments can be taken out of service without 20 interrupting the circulation of air through the other compartments. For this purpose, a common exhaust header 49 is provided having perforated intake pipes 50, 51 and 52 each located near the top of one 25 of said compartments and each being adapted to be controlled by a butterfly valve 53. The outlet for the header 49 is through a pipe 54 communicating with the upper end of the header and having two outlet pipes 30 55 and 56 controlled by valves 57 and 58 and terminating outside of the compartments. Within the upper compartment, the pipe 54 is enclosed by a jacket 59 through 35 which a cooling medium from the common 40 refrigeration system for the compartments may be passed.

The movable members of the valves 57 and 58 are connected by a rod 60 which is adapted to be actuated by a lever 61 of a 45 diaphragm unit 62 and which is also arranged to actuate a rod 63 carrying six valve members 64 and 65 for controlling six inlet ducts or ports 66 and 67. Two of these 50 ports are provided in each compartment, and located respectively near the upper and lower portions of the compartment. The unit 62 has temperature responsive pressure 55 elements 68 and 69, one being located within one of the compartments, the other being placed outside of the compartments.

When the temperature outside of the compartments is greater than that inside, the valves 58 and 64 will be open and the others will be closed as shown in Fig. 4. Then, as 60 the air in the pipe 54 becomes cool, it moves downwardly thereby inducing circulation into the exhaust header 49 from the pipes of the several compartments and out of the pipe 56 through the valve 58. The compartments are replenished with fresh air through

the ports 66. Now, when the temperature conditions are reversed, the unit 62 will operate to open valves 57 and 65 and to close valves 58 and 64. Under these conditions, 70 the outside air being colder and denser than the air in the compartments will tend to move into each of the compartments through the open ports 67. This inflow of air together with the tendency of the lighter air within the compartments to rise and flow 75 through the header 49 out of the open pipe 55 will effectually remove the foul air from the top of each of the compartments. By means of the valves 53 it will be observed 80 that any of the compartments can be taken out of service without interfering with the natural circulation of air through the other compartments. In other words, by closing 85 one of the valves 53, the intake pipe leading to the header 49 will be closed without interfering with the setting of the valves which regulate the direction of the circulation of air in the system as a whole.

I claim as my invention:

1. The combination with a compartment 90 to be ventilated, of an exhaust header having inlets located within said compartment and two outlet ducts from said header both leading out of said compartment, one of said outlets being positioned substantially above 95 the other, two inlets to said compartment, one located substantially above the other, and valve means controlling said outlets and inlets and operable to open said upper outlet and said lower inlet while closing said 100 upper inlet and said lower outlet.

2. The combination with a compartment 105 to be ventilated, of means adapted to provide two different paths for the circulation of air into and out of said compartment, valve means for establishing either one or the other of said paths of circulation, and means responsive to the differential between the temperature inside and outside of the compartment for controlling said valve 110 means selectively.

3. The combination with a compartment 115 to be ventilated, of means providing two different paths for the circulation of the air outside of the building in which said compartment is located into and out of said compartment, valve means operable to establish either one or the other of said paths of circulation selectively, operating means for said valve means including a pair of thermal responsive pressure elements, one located in 120 said compartment and the other located outside of said building, and means actuated by said elements to operate said valve means when the outside temperature becomes greater or less than the temperature within said compartment.

4. The combination with a compartment 125 to be ventilated, of an exhaust conduit having inlets within said compartment, means

adapted to provide two different paths for the circulation of air into said compartment and out of said compartment through said conduit, and valve means for establishing either of said paths of circulation, and a single operating means for said valve means.

5. The combination with a compartment to be ventilated, of an exhaust header having inlets located in the upper portion of 10 said compartment, means adapted to provide two different paths for the circulation of air into said compartment and out of said compartment through said header, valve means operable to establish either of said 15 paths of circulation, and means operable when the temperature outside of said compartment exceeds the temperature therein to actuate said valve means to establish one of said paths of circulation while closing the 20 other path and when the temperature outside of said compartment is less than the temperature within the compartment to actuate said valve means to close said first mentioned path and establish said other path 25 of circulation.

6. The combination with a plurality of compartments to be ventilated, of an exhaust header having inlet openings within each of 30 said compartments, valves each controlling one of said inlets, two outlet ducts leading from said header and terminating outside of

said compartments at different levels, means adapted to cool the air in one of said ducts to a temperature below that of said compartments, two inlet ducts for each of said compartments located respectively near the upper and lower portions of the corresponding compartment, a valve for each of said cutlet ducts, and a valve for each of said inlet ducts.

7. The combination with a plurality of compartments to be ventilated, of an exhaust header having inlet openings within each of said compartments, valves each controlling one of said inlets, two outlet ducts leading from said header and terminating outside of said compartment at different levels, means adapted to cool the air in one of said ducts to a temperature below that of said compartments, two inlet ducts for each 40 of said compartments located respectively near the upper and lower portions of the corresponding compartment, a valve for each of said outlet ducts, a valve for each of said inlet ducts, and means for operating 45 said inlet and said outlet valves in accordance with the differential between the temperatures inside and outside of said compartments.

In testimony whereof, I have hereunto 50 affixed my signature.

GEORGE HILGER.
